CONTROL SYSTEM

Eugene D. Stirlen and Charles D. Geer, New Haven, Conn., assignors to The Engineering and Research Corporation, New Haven, Conn., a corporation of Connecticut

Application December 26, 1930, Serial No. 504,732

4 Claims. (Cl. 177—337)

This invention relates to a functionally and structurally improved traffic signaling system.

It is an object of the invention to provide an apparatus of this character which will function responsive to changing conditions in traffic in such manner that the traffic may move with maximum expediency and minimum interruption of right of way. Accordingly, a large number of vehicles may move past an intersection which is provided with a lay-out of apparatus embodying the present invention, and the flow of traffic will have less liability of congestion than is otherwise the case.

A further object of the invention is that of construction of an apparatus for use in connection with the control of traffic and by means of which, after the variable traffic conditions existing at any particular point of installation have been determined, the apparatus may be set to meet these conditions.

A still further object of the invention is that of furnishing a traffic control system in which, if it is found that the conditions decided upon are not correct, or if these conditions vary, the parts may be adjusted so that the apparatus will function to give the best obtainable results.

Another object is that of furnishing an apparatus of the character described, the parts of which will be relatively few in number and individually simple and rugged in construction, these parts being readily assembled, and when so assembled operating over long periods of time with freedom from mechanical and/or electrical difficulties.

Reference is had to the attached sheet of drawing illustrating one practical embodiment of the invention, and in which:

Fig. 1 represents diagrammatically a lay-out of apparatus embodying a traffic control system, and

Fig. 2 is an end view of one unit of such apparatus.

In the foregoing figures, and the subsequent specification, the invention will be described in connection with a traffic control apparatus, the operation of which is governed by timers having predetermined cycles of operation, rather than a traffic control system which is controlled automatically by the density of traffic, or, in other words, is vehicle operated. While in certain respects the present invention lends itself ideally for use in connection with a system including fixed cycle timers, it is at this time to be understood that it may be employed in conjunction

with various other types of systems and specifically traffic controlled systems.

Moreover, as illustrated and described, the depicted form of the invention is to be applied at the intersection of two vehicular lanes in which, at certain times of the day, there exists substantially equal traffic dignity, and, moreover, traffic of a certain density, while at other times of the day the density remains equal in so far as the two lines are concerned, but the volume of traffic increases. Additionally, for the sake of illustration, these lines are assumed at certain times of the day to have an unbalanced condition of traffic density. In other words, during those times the first vehicle lane will have a relatively small traffic flow, while the second vehicle lane will have a relatively major traffic flow. Obviously, the conditions set forth are merely illustrative and might be varied, modified or amplified in many respects, without departing from the spirit of this invention.

Thus, as in Fig. 1, there has been indicated in dotted lines streets A and B. Signaling means is shown at the point of intersection of such streets and has been indicated by the reference numeral 1. This signaling apparatus may embrace simply a lamp which displays, toward the approaches of the several streets, covered lenses, bulbs, and/or reflectors, the coloration of which is usually red and green, the former indicating "stop" and the latter according right of way. Obviously, any suitable type of signaling means might be employed, the foregoing being merely the one usually utilized, and the simplest form. The "go" and "stop" signals of B street have been indicated respectively by the reference letters G' and R and the "go" and "stop" signals of A street have been indicated as G and R' respectively. A suitable source of electric current supply is connected with the leads 10 and 11, and the first lead is connected by a branch 12 to supply one side of the bulbs G, G', R, R'.

At 2, 3 and 4 there have been shown three different timers, the construction of which, however, is generally similar, with the exceptions hereinafter noted. These timers may each include a motor 13 which, by means of a drive shaft 14, rotates a shaft 15. Considering, now, timers 2 and 4 for example, this shaft supports a contact segment 16 and an insulating segment 17, which will be sequentially traversed by a stationary brush or wiping arm 18 as the shaft 15 rotates. This brush is connected to one side of a magnet 19, the opposite side of which is connected to a lead 20.

An armature 21, controlled by the magnet 19, is connected to the lead 22 when the magnet is not energized. This condition of the parts may be assured either by gravity or spring pressure, 5 as may be deemed best. When attracted by the magnet 19, the armature 21 is connected to the lead 23. The armature 21 is, in turn, in series with a lead 24 which is connected to lead 25 coupled to one of the posts of the motor, while 10 lead 20 is connected to lead 26 coupled with the second binding post of the motor. Also, a lead 27 is provided which is connected to the lead 25 and to the contact segment 16. Thus, it will be obvious that if current is supplied to leads 25, 15 26, the motor 13 will operate and as the segment 16 moves into engagement with the brush 18, the magnet 19 will be energized to attract the armature 21, thus to supply current to lead 23 and consequently to bulbs G' and R'. Accordingly, 20 there will be right of way in favor of B street and interruption of right of way on A street. However, assuming that the segment 17 is in contact with the brush 18, and conceding that current is supplied to leads 25, 26, current 25 will flow to lead 22, thus energizing the bulbs R and G, with the result that right of way is transferred in favor of A street.

The motor, or the drive therefor, of unit 2 is timed to give one revolution per minute to the 30 shaft 15, and in view of the fact that the segments 16 and 17 are of equal length, it will, accordingly, be obvious that transfer of right of way will follow every thirty seconds, so long as current is supplied to leads 25, 26. The unit 3, 35 which is otherwise generally similar to units 2 and 4, has a non-conducting segment 28 which extends throughout substantially two-thirds of the circumference, or path, of the brush, and a conducting segment 29 extending throughout 40 substantially one-third of this circumference or path. Accordingly, when unit 3 is operating to the exclusion of unit 2 and unit 4 (which latter will be hereinafter described), and if current is supplied to the leads 25, 26 of unit 3, right of way 45 will occur in favor of B street for approximately a twenty second period and in favor of A street for substantially forty seconds.

The unit shown at 4 is, in all respects, similar to the unit 2, with the exception, however, that 50 either the motor or the drive of this unit is so timed that only one-half revolution per minute is made on the part of the conducting and non-conducting segments. Accordingly, while right of way periods of equal intervals will occur in 55 favor of A and B streets, these right of way periods will each be for a time interval of sixty seconds.

Now, with a view to providing means which will 60 control the supply of current to the several timer units, and accordingly control the operation of the system, attention is invited to the mechanism generally indicated at 5. At this point the numerals 30 and 31 indicate electromagnets. The former, when energized, attracts armatures 32 65 and 33 which are connected respectively to the leads 10 and 11, and connectible to the leads 25 and 26 of unit 2. Energization of this magnet also attracts armatures 34 and 35, which are normally connected to leads 25, 26 of unit 3, and 70 from which leads 36, 37 extend. Position of the armatures, as shown in Fig. 1, is not only maintained as, for example, by gravity or the use of springs (not shown) but the magnet 31 controls the position of armatures 38, 39, 40 and 41; armatures 38 and 41 being connected to lead 10,

and armatures 39 and 40 being connected to lead 11. In the normal position of the parts, armatures 40, 41 are connected to leads 36, 37, and in view of the normal position of the armatures 34, 35, current usually flows from power supply 5 leads 10, 11 to unit 3. However, upon energization of magnet 30, current flow to unit 3 is interrupted by the movement of armatures 34, 35, while current flow to unit 2 occurs incident to the connection of armatures 32, 33 to the leads 10 25, 26 of this unit. On the other hand, when magnet 31 is energized, current flow to unit 3 is interrupted by movement of the armatures 40, 41, while current is supplied to unit 4 due to the connection which comes into being between armatures 38, 39 and the leads 25, 26 of this unit.

In the controlling mechanism heretofore described, and generally indicated at 5, a governing unit of, for example, the nature shown in the right-hand corner of Fig. 1 and indicated at 20 6, is employed. This may comprise, as illustrated, a drum 42 rotatably mounted upon a shaft 43. This drum is of non-conducting material, but has a conducting wiper ring 44 engaged by a brush 45 which, through a lead 46, is connected 25 to the power supply 11. The ring 44 has an electrical connection with contact segment, or segments, 47 carried by the drum, and this segment preferably, but not necessarily, has a straight lead edge and a biased, or tangentially 30 extending trailing edge, it being noted that the segment may be removed and replaced by a segment of different configuration, if this is desired. Supporting rods 48, 49 extend adjacent to the drum and adjustably mount brushes or contact 35 members 50. It may be locked in position as, for example, by use of set screws 51. These brushes may be of any desired type and, for example, spring-pressed (not shown), but in any event they contact with the plate 47 as the latter 40 traverses their point of mounting. The brushes or contact members are in electrical connection with leads 52, 53, as, for example, by having the rods of conducting material, and these leads extend toward, and are connected to, the power 45 lead 10, and have in series the magnets 30 and 31, respectively.

Any desired mechanism for controlling the movements of the drum may be employed. Such a mechanism may be, for example, an electric 50 motor 54 which, by means of a suitable reduction drive (not shown) rotates the drum steadily once every twenty-four hours. The motor is supplied current through the lead 46 and the lead 55, which latter is connected to lead 10 as well as to 55 the leads which supply armatures 32, 35, 38 and 41. In the example given, the street intersection has been classified as that type at which the following conditions occur. The flow of traffic during the greater part of the day is such that maximum 60 efficiency is gained by alternately giving right of way for forty seconds to A street and then for twenty seconds to B street, and repeating this cycle for the number of hours which have previously been determined on. This would apply, 65 for example, from seven o'clock in the evening until twelve o'clock noon. From that time until 2 P. M., the midday traffic might be equal on both streets, and maximum efficiency gained through the use of a cycle which accords alternately right of way for thirty seconds to each 70 street. From 2 P. M. to 5 P. M. the first cycle might be returned to, and at 5 P. M. most dense traffic of the day might commence for both streets. While now the traffic may be of substan- 75

5 tally equal volume, on both streets, maximum efficiency is gained by allowing each street a longer period of right of way, for example, sixty seconds. This condition will theoretically prevail until 7 P. M., at which time the operation will revert to the initial condition set forth in the beginning of this paragraph. Control of this nature will obviously follow for the reason that, as shown, current is being supplied the unit 3 to 10 accord the forty-twenty second cycle heretofore referred to. When the plate 47 engages the contact 58 of rod 48, magnet 30 is energized, thereby discontinuing the operation of unit 3 and initiating the operation of unit 2. This furnishes 15 the thirty-thirty second cycle of operation. When plate 47 engages the brush or contact associated with rod 49, current will flow through magnet 31, thus disconnecting unit 3 and connecting unit 4 for operation to furnish the sixty- 20 sixty second cycle of operation. Obviously, by having the rods 48 and 49 adjustably mounted, as, for example, by the arcuate slot construction indicated at 56, in Fig. 2, the rods and brushes or contacts carried thereby may be shifted so as to 25 have the periods begin at any desired time. To this end, indicia 57 may be provided so that the value of the adjustment will readily be apparent. Moreover, if it is desired to lengthen the periods 30 of energization of either of the magnets 30 or 31, this may be achieved by adjusting the brushes 58 along the rods 48 or 49, so as to extend to the desired point the period of energization, it being noted that this occurs due to the increasing 35 width of the plate 47. Also, the rods 48, 49 may be sub-divided in the manner shown in order to indicate the value of the adjustment provided.

As afore brought out, the illustrated embodiment of the invention is diagrammatic and for the purpose of showing one form which the invention may take. It is obvious that the number of units or sub-units controllable might be varied according to the needs of the installation, that the time control of these units might also be changed, and that the features of the present 45 invention might be employed in connection with virtually any desired type of traffic control system, or in other installations where the invention might be of value, and that the structural details are subject to rearrangement and reconstruction, as may be deemed expedient to the 50 needs of the installation, all of which may occur without departing from the scope of the invention as defined by the claims.

Having described my invention, what I claim 55 as new and desire to secure by Letters Patent, is:

1. In a traffic control system, signaling means for according and interrupting right of way, a plurality of timers connectible to said signaling means and each when connected functioning to cause the display of said signaling means in accordance with a plan differing from those of the other timers, and constantly and automatically acting control means common to all of said timers and time-controlled to selectively couple 60 said timers to said signaling means in a program cycle in which one of said timers has a period of operation alternating between those of two of the other timers, and means for varying said control means by a single adjustment to vary the relative lengths of successive periods of said one of said timers and means for separately adjusting the lengths of the periods of operation of the other timers.

period of operation alternating between those of two of the other timers, and means for varying said control means by a single adjustment to vary the relative lengths of successive periods of said one of said timers while the sum of said successive periods remains constant. 5

2. In a traffic control system, signaling means for according and interrupting right of way, a plurality of timers connectible to said signaling means and each when connected functioning to 10 cause the display of said signaling means in accordance with a plan differing from those of the other timers, switching means for connecting said timers to said signaling means and a constantly operating time-controlled switch mechanism for operating said switching means to effect successive connections and disconnections of said timers, said switching means including one relay means operating when energized to connect one of said timers, another relay means operating when energized to disconnect said one of said timers and to connect another of said timers, the two relay means being arranged when both are de-energized to disconnect the last two mentioned 15 timers and to connect a third timer. 20

3. In a traffic control system, signaling means for according and interrupting right of way, a plurality of timers connectible to said signaling means and each when connected functioning to 25 cause the display of said signaling means in accordance with a plan differing from those of the other timers, switching means operable when energized for connecting one of said timers to said signaling means, a second switching means operable when energized to disconnect said last-mentioned timer and connect another timer, said two switching means being arranged when both are de-energized to disconnect the last two mentioned timers and to connect a third timer, and 30 a constantly operating time-controlled switching mechanism for sequentially operating said first and second named switching means in a program in which both of said switching means are de-energized between periods of alternate energiza- 35 tion of said first and second switching means. 40

4. In a traffic control system, signaling means for according and interrupting right of way, a plurality of timers connectible to said signaling means and each when connected functioning to 45 cause the display of said signaling means in accordance with a plan differing from those of the other timers, constantly and automatically acting control means common to all of said timers and time-controlled to selectively couple 50 said timers to said signaling means in a program cycle in which one of said timers has a period of operation alternating between those of two of the other timers, and means for varying said control means by a single adjustment to vary the relative lengths of successive periods of said one of said timers and means for separately adjusting the lengths of the periods of operation of the other timers. 60
